UNITED STATES PATENT OFFICE

164,769

WALLET

Henry R. Godfrey, Gardner, Mass.

Application March 10, 1950, Serial No. 8,444

Term of patent 14 years

(Cl. D87—3)

To all whom it may concern:

Be it known that I, Henry R. Godfrey, a citizen of the United States, residing at Gardner, in the county of Worcester and State of Massachusetts, have invented a new, original, and ornamental Design for a Wallet, of which the following is a specification, reference being had to the accompanying drawing, forming part thereof.

Fig. 1 is a plan view of the inside of a wallet embodying my new design, and

Fig. 2 is a top edge view of the wallet as shown in Fig. 1.

The outside of the wallet is conventionally plain.

My design for a billfold of the conventional folding type having an open bill pocket and two open card pockets, the left hand card pocket being provided with a transparent window, is characterized by the tulip cut-out near the bottom center of the right hand card pocket in association with the asymmetrical curve of the top of said pocket.

I claim:

The ornamental design for a wallet, as shown and described.

HENRY R. GODFREY.
